UNITED STATES PATENT OFFICE.

CHARLES HOFF, OF CINCINNATI, OHIO, ASSIGNOR TO HOFF, NOLL & RENNER.

SHEET-METAL-SEAMING MACHINE.

SPECIFICATION forming part of Letters Patent No. 314,448, dated March 24, 1885.

Application filed June 3, 1884. (No model.)

To all whom it may concern:

Be it known that I, CHARLES HOFF, a citizen of the United States, and a resident of Cincinnati, in the county of Hamilton and State of Ohio, have invented certain new and useful Improvements in Sheet-Metal-Seaming Machines, of which the following is a specification.

This invention relates to seaming machines, and especially for preparing roofing-tin. Its object is to rapidly form the seam and roll the tin ready for use. With this object in view my invention consists in mechanism for feeding the sheets forward, forming the seams, and 15 rolling the formed sheets ready for use.

The invention will be first fully described in connection with the accompanying drawings, and then particularly pointed out in the claims.

20 In the accompanying drawings, in which similar reference-letters indicate like parts wherever they occur, Figure 1 is a side elevation of my improved machine. A portion of the side frame and bed-plate is broken away to show an end view of the clamping-jaws. Fig. 2 is a vertical transverse section taken in front of the treadle and clamping-jaws. In this view a portion of the bed-plate is removed on the right-hand side to expose part of the lower 25 clamping-jaw. Fig. 3 is a top plan view of the head of the machine. Fig. 4 is an enlarged detail view in vertical transverse section of the jaws, exposing one of the stop-pins which check the sheets in position to be acted 30 upon by the seam-forming jaws. In this view the edges of the two sheets are shown hooked together between the jaws, ready to receive the pressure necessary to form the seam.

The frame of the machine consists of two 35 side standards, A, which support the bed-plate B, and are braced together by the cross-bars a. The bed has a folding extension, B', which is hinged to the bed-plate B, and supported in the working-position, Fig. 1, by a support, b. When the machine is not in use, this tail-board B' folds down to economize 40 space. Upon the opposite end of the machine are two brackets, C, one upon each side, to support the removable winding-roller E, which 45 is provided outside of the brackets with a crank, e, and on the same side, within the bracket, with a ratchet-wheel, F, the teeth of which

are engaged by a spring-pawl, f, to prevent the tin from unwinding.

Secured rigidly to the frame of the machine 55 and above the bed-plate B is the stationary beam G. This is vertically perforated to receive the stop-pins g. From this beam G is suspended by bracket-irons h another beam, H. Between the two stationary beams G H 60 the movable jaw I is supported by the toggle-joints J, which are united to the pitman K by the links j j. The movable jaw I plays through a slot in the bed-plate, the walls of which guide it vertically against or from the stationary jaw 65 G. The treadle-bar L is fulcrumed at l in lugs secured to the floor or foundation, and, passing under one of the cross-braces to the outside of the frame, is provided with a hinged foot-plate, l', which may be folded up out of 70 the way when the machine is not in use. The treadle-bar, striking against the under side of the cross-bar a, prevents the jaw I from dropping down too far. It is only necessary that the jaw I drop just below the top of the table 75 to permit the tin to be carried forward. A spring, N, is shown stretched between the beam H and the treadle to assist in operating the jaws.

I have shown the roller E provided with a 80 central removable collar, e', and a removable end plate, e'', on the end opposite from the ratchet-wheel. The wheel e'', collar e', and ratchet-wheel F guide the sheets true on the roller.

The machine shown is intended to form two strips at once, but it may be made to form any 85 desired number.

The tin sheets M to be joined have their opposite edges hooked in opposite directions 90 in the usual manner.

The mode of operation of my device is as follows: The opposite edges of the sheets M being hooked together, the hooked parts are passed between the jaws G I. The treadle is 95 then brought down and the joints pressed together and formed. The sheets are then advanced until another joint is brought under the action of the jaws, and so on until a strip long enough to reach the roller E is formed, 100 when the leading downwardly-bent end of the sheet is placed in a slot in the roller. The machine is now ready for continuous rapid work. It will be noticed that as the sheets

M advance the pins *g* rest upon them. The tin is now wound around the roller E until the hooked edges are stopped by the pins, which have rounded lower ends. The treadle 5 is now brought down, closing the jaw I up against the stationary jaw G, thus forming another seam. So soon as the jaw I is allowed to drop by releasing the treadle the crank *e* is moved, winding the sheet around the roll (the 10 flattened seam readily passing the stop-pins, which slide up in the stationary jaw G) until the sheets are again stopped by the pins *g*, when the treadle is again brought down, forming another seam, and so on until a sheet or 15 sheets of sufficient length are formed. During this operation the operator supplies new plates of tin, as required, with one hand, while operating the crank with the other hand and the treadle with the foot. When sheets of 20 sufficient length have been formed, the roller E is removed, stripped, and returned preparatory to forming other sheets. It will thus be seen that I have produced a compact cheap 25 machine which requires but little power to operate, and which leaves the tin in good condition to be applied for roofing purposes. I thus, by avoiding the buckling and uneven joints usually made, save much time in applying the tin to use, and insure better work.

30 What I claim, and desire to secure by Letters Patent, is—

1. In a tin-seaming machine, the combina-

tion, substantially as specified, of the frame A, the bed B, transversely slotted to pass the movable member of a clamping device, with 35 toggle-jointed levers actuated by a treadle to bring the said movable jaw up against the stationary jaw for the purpose of closing the seam.

2. In a seaming-machine, the combination 40 of the stationary jaw provided with gravitating stop-pins to check the hooked joints beneath the said stationary jaw with a movable jaw constructed to be forced up against said stationary jaw to form the completed seam, 45 substantially as specified.

3. A seaming-machine consisting of a bed-plate, a pair of clamping-jaws arranged to operate upon a hooked sheet of tin passing over said bed-plate, a removable winding-roll to 50 draw the sheet forward and roll it up for use after the seams are formed, and a guide (one or more) removably secured to the roll, substantially as herein shown and described.

4. In a seaming-machine, the combination, 55 substantially as hereinbefore set forth, of the frame, bed-plate B B', and clamping-jaws G I, with stop-pins *g*, and removable roller E, ratchet F, and pawl *f*.

CHARLES HOFF.
